D. Anthony, Esq.

UNITED STATES PATENT OFFICE.

FRANK PARDEE, OF HAZLETON, PENNSYLVANIA, ASSIGNEE TO ANTHRACITE SEPARATOR COMPANY, A CORPORATION OF PENNSYLVANIA.

SPIRAL SEPARATOR.

Application filed October 10, 1921. Serial No. 506,755.

To all whom it may concern:

Be it known that I, FRANK PARDEE, a citizen of the United States, and resident of Hazleton, Pennsylvania, have invented 5 certain new and useful Improvements in Spiral Separators, of which the following is a specification.

This invention relates to spiral separators and particularly to points of construction 10 whereby the flare or downward pitch may be increased or decreased as desired, and to means for controlling the elevation to which the material must climb before it can fly or skim off the runway.

15 The invention is illustrated in the accompanying drawings in which

Fig. 1 is a side elevation of a portion of the separator with parts shown in section to clearly illustrate the present improvement;

20 Fig. 2 is a fragmentary plan on a larger scale of parts shown in Fig. 1;

Fig. 3 is an enlarged sectional view.

In the drawings 1 represents the usual 25 central supporting post, 2 the outwardly and upwardly extending supporting rods to which are secured the fixed segments or jackets 3 of the runway. The jackets 3 are substantially triangular in shape and overlap 30 one another at their radial edges so as to form a continuous spiral floor or runway. This runway is of known construction and is built at a fixed pitch or downward and inward inclination as illustrated 35 in Fig. 3, the angle of inward inclination being governed according to the class of material to be handled by the separator.

To the runway 3 I secure a series of pitch reducing plates 4 by means of rivets 5. 40 The plates follow the general outline of the spiral runway but their inner ends 6 are raised so as to leave a space 7 between themselves and the floor or runway 3, thus these pitch reducing plates have a more gentle 45 downward inclination or pitch than the fixed plates 3 of the runway. At the outer or peripheral edge of the runway I secure a series of plates 8 forming a continuous flange adapted to prevent material from creeping up and flying off the outer portion 50 of the separator. To the outer face of the plates 8 I adjustably secure other plates 9 by means of clamp bolts 10 which pass

through slots 11 formed in plates 9, suitable nuts 12 being carried by the bolts 10 to clamp 55 the plates 9 at the desired elevation.

This construction permits a separator having a fixed pitch or downward inclination to be constructed so that the outer portion thereof will have a more gentle pitch and thereby tend to hold the purer coal in the outer zone. The plates 4 may be perforated or otherwise roughened to increase the frictional effect on the material traveling thereon, such frictional surface being indicated 60 at 4^a in Fig. 2. All the plates 4^a may be provided with such frictional surfaces or alternate plates can be so arranged according to the requirements of the particular 65 class of coal being handled.

The structure herein illustrated is particularly adapted for handling coal or other materials of substantially round fractures which gather considerable momentum traveling on the separator and which are not 70 as easily governed as other classes of coal. The outer flanged members 8 are effective to prevent the coal from flying off the runway at a high velocity and the adjustable plates 9 provide means whereby the height 75 at which the coal is permitted to skim off the runway can be controlled, it being apparent that raising or lowering the plates 9 the distance which the coal has to climb can be readily varied so as to make it more 80 or less difficult for the purer coal to skim or fly off the outer portion of the runway. The purer coal which is skimmed or flies off the outer portion of the runway is caught by an outer conveyor thread 13 having an 85 upwardly flared flange 14 of sufficient height to catch all of the material discharged from the separator thread. This conveyor thread is of known construction and is supported in the usual manner by 90 radial rods 15 secured to the central post. At the lower end 16 the conveyor thread connects with a discharge chute, not shown, leading to a suitable storage bin. At the lower end of the separator are mounted 95 100 chutes 17 and 18 adapted to receive respectively the pure coal which flows along that portion of the runway formed by the plates 4, and the slate and other refuse which flows along the inner portion of the runway which 105 is made up of the fixed plates 3. These

chutes 17 and 18 also lead to suitable storage bins, not shown.

It is known to those skilled in this art that the purer coal is of a more smooth and glossy surface than the slate and other impurities and that it flows more freely over inclined surfaces. In operation the mixture of pure coal, slate and other impurities is fed to the outer portion of gentle pitch at the upper end of the separator and as the material travels downwardly the purer coal separates from the slate and impurities and travels in an outer path, the friction surfaces on the plates 4^a and the natural characteristics of the slate and impurities tending to retard their movement and cause them to move gradually inward and finally fall off on to the inner portion of the runway formed by the plates 3. Those lumps of coal which are of a purer grade travel at a considerably higher rate of speed than the other lumps and gradually climb up the flanges 8 and plates 9 and are caught by the conveyor thread 14. The intermediate grade of pure coal travels along the portion of the runway formed by the plates 4 and is discharged through chute 17 to a suitable storage bin and the slate, boney coal and other impurities are discharged through chute 18 to a suitable refuse pile. Any lumps of slate or other impurities travelling slowly enough to fall over the edge 6 of the plates 4 will not have sufficient momentum when reaching the runway 3 to tend to carry them outward and under the plates 4. In fact such lumps will tend to travel inward toward the central post 1 due to the steeper pitch or inward inclination of the runway 3.

While I have described with great particularity the embodiment of the invention herein illustrated, it is not to be construed that I am limited thereto and it is to be understood that the illustrations and the foregoing description are to be interpreted in an illustrative rather than a limiting sense, as various modifications may be made without departing from the scope of the invention as defined in the appended claims.

What I claim is:

1. A spiral separator having a runway comprising a series of inwardly and downwardly inclined segmental plates and a series of plates secured to the outer portion of said segmental plates having their inner ends spaced above the surface thereof to form an outer runway of less inward in-

clination than the inclination of the first mentioned segmental plates.

2. A spiral separator having a runway 60 comprising a series of inwardly and downwardly inclined segmental plates, upwardly extending flanged plates secured to said segmental plates and means carried thereby for adjusting the height of said flange so as to control the elevation at which the material will be permitted to skim off of the separator.

3. A spiral separator having a runway 70 comprising a series of inwardly and downwardly inclined segmental plates and a series of plates secured to the outer portion of said segmental plates having their inner ends spaced above the surface thereof to form an outer runway of less inward inclination than the inclination of the first 75 mentioned segmental plates and means associated therewith for varying the distance which material must climb in order to skim off of the runway.

4. A spiral separator comprising a central supporting post, a series of outwardly and upwardly extending supporting rods carried thereby, fixed segmental plates secured to said supporting rods, a series of 85 outer arcuate plates carried by said fixed segmental plates and having their inner ends spaced above the surface thereof so that they are inclined to a lesser inward angle than said fixed segmental plates, an 90 outer upwardly extending flange secured to said segmental plates and means secured to said flange for varying the effective height thereof.

5. A spiral separator having a runway 95 over which the materials to be separated travel, the inner and outer portions of said runway being inclined inwardly and downwardly at different angles.

6. A spiral separator comprising a runway 100 over which the materials to be separated travel, said runway having an inner portion inclined inwardly and downwardly at a comparatively steep angle and an outer portion also inclined inwardly and downwardly but at a more gentle angle than said inner portion the portions of the runway being so arranged that certain classes of material can travel from the outer portion to the inner portion.

In witness whereof, I have hereunto signed my name.

FRANK PARDEE.
